[57] CLAIM

The ornamental design for a cellular telephone, as shown and described.

DESCRIPTION

FIG. 1 is a front, top and right side perspective view of a cellular telephone environmentally mounted partially within a sunvisor;

FIG. 2 is a top plan view of the cellular telephone shown within the broken lines depicting the sunvisor; FIG. 3 is a left end elevational view of the cellular telephone as shown in FIG. 1;

FIG. 4 is a bottom end elevational view of the cellular telephone shown in FIG. 1; and,

FIG. 5 is a rear plan view of the cellular telephone as shown in FIG. 1.

The broken line showing of a sun visor in all five figures is for illustrative purposes only, and forms no part of the claimed design.
